(21) Appl. No.: **29/687,359**

The ornamental design for a combined front bumper and grille for a vehicle, as shown and described.

(22) Filed: **Apr. 12, 2019**

DESCRIPTION

(30) **Foreign Application Priority Data**

Oct. 25, 2018 (EM) 005808441

FIG. 1 is a top, front and left side perspective view of a combined front bumper and grille for a vehicle showing my new design;

(51) **LOC (12) Cl.** **12-16**

FIG. 2 is a left, front perspective view thereof;

(52) **U.S. Cl.**

FIG. 3 is a bottom, rear and right side perspective view thereof;

USPC **D12/169**

FIG. 4 is a right, rear perspective view thereof;

(58) **Field of Classification Search**

FIG. 5 is a front elevational view thereof;

USPC D12/169, 164, 196, 171, 163, 86, 90-92;
293/102, 113, 115, 117, 120; 296/180.1,
296/180.2

FIG. 6 is a rear elevational view thereof;

CPC B60R 19/02; B60R 19/04; B62D 25/08
See application file for complete search history.

FIG. 7 is a left side elevational view thereof;

(56) **References Cited**

FIG. 8 is a right side elevational view thereof;

U.S. PATENT DOCUMENTS

FIG. 9 is a top plan view thereof;

D746,733 S * 1/2016 Behmer D12/169
D747,243 S * 1/2016 Patel D12/169
D779,396 S * 2/2017 Patel D12/169
D784,215 S * 4/2017 Peat D12/169
D801,887 S * 11/2017 Peat D12/169
D820,741 S * 6/2018 Patel D12/169
D837,109 S * 1/2019 Kozub D12/169

FIG. 10 is a bottom plan view thereof; and,

FIG. 11 is another front elevational view thereof shown on a vehicle.

The portions of the vehicle shown in the FIG. 11 drawing view in a de-emphasized and half-tone form outside the broken lines and the broken lines representing the boundary and configuration of what is claimed as the design are all for environmental and illustrative purposes only and form no part of the claimed design.
